(57) **CLAIM**

The ornamental design for a front opening cigarette box, as shown and described.

DESCRIPTION

FIG. 1 is front elevational view of a front opening cigarette box in its closed condition, showing my new design;

FIG. 2 is a right side elevational view thereof, the left side elevational view being a mirror image duplicate;

FIG. 3 is a rear elevational view thereof,

FIG. 4 is a top plan view thereof;

FIG. 5 is a bottom plan view thereof;

FIG. 6 is a left side elevational view of the front opening cigarette box in its opened condition, the right side elevational view being a mirror image duplicate;

FIG. 7 is a front elevational view of the front opening cigarette box in its opened condition; and,

FIG. 8 is a top plan view of the front opening cigarette box in its opened condition.

The broken lines are shown for illustrative purposes only and form no part of the claimed design.
